UNITED STATES PATENT OFFICE.

JAMES HERBERT McDERMOTT, OF HARTFORD, CONNECTICUT.

FABRIC-MEASURING DEVICE.

Application filed June 3, 1924. Serial No. 717,571.

To all whom it may concern:

Be it known that I, JAMES HERBERT McDERMOTT, a citizen of the United States, residing at Hartford, in the county of Hartford and State of Connecticut, have invented certain new and useful Improvements in a Fabric-Measuring Device, of which the following is a specification.

This invention relates to an improved fabric measuring device which is especially, but not necessarily, intended for counter use in department stores and the like.

I have evolved and produced a novel measuring device of the above named class which is exceedingly practical and desirable for use by novices and apprentices to enable them, without instructions, to accurately cut and make sales for any amount of material solicited by a customer.

Briefly and broadly speaking, the improved device comprises a calibrated body which is provided at predetermined longitudinally spaced points with suitable guides for a cloth severing implement, which is in the most instances a pair of scissors.

More specifically, I propose to utilize a device of the above class which preferably comprises a pair of calibrated or graduated straight edges which are provided at longitudinally spaced points with scissor blade receiving grooves, these straight edges being connected together by scissor guides which have their opposite ends opening into the respective grooves in the straight edges.

The several features and advantages of the invention will become apparent from the following description and drawing.

In the accompanying drawing forming a part of this specification and in which like numerals are employed to designate like parts throughout the same:

Figure 1 is a top plan view of the fabric measuring device constructed in accordance with this invention.

Figure 2 is an enlarged detail section showing the method of connecting the parts.

Figure 3 is a detail perspective view of one end of the hereinafter referred to guides.

In carrying out the invention, I provide a structure which is capable of being built into an ordinary store counter, rigidly connected thereto, or movably supported thereon. In the drawing however, I have shown the improved device detachably connected with the upper surface of the counter, the same being arranged at any convenient point

upon the latter. The counter is represented by the reference character 1, and the measuring device as a whole, is designated by the reference character 2. While the device last mentioned could be constructed in some other manner, I prefer to use two strips of brass or equivalent material 3. Each of these strips is slightly greater than thirty six inches in length, this length having been found sufficient to meet substantially all requirements of the device. These brass strips constitute the so called straight edges. As more clearly seen in Figure 1, each strip is calibrated by providing it with one-inch 70 graduations for both the customer and salesman to observe in measuring off the desired piece of fabric. Also as seen in the figure last mentioned, each of the brass strips is provided at predetermined longitudinally spaced points with transverse grooves 5, and for the purpose of detachably connecting the strips with the counter 1, they are provided with holes for passage of fastening screws or the like.

In practice the measuring strips are disposed along the opposite longitudinal edges of the counter so that the device takes up substantially a space in width equal to the width to a conventional bolt of fabric. Of course, in attaching the measuring strips, they are placed in spaced parallelism and as seen, a plurality of longitudinally spaced wooden strips 6 are interposed between the inner edges thereof. Each wooden strip is provided in its top with a groove 7 extending from end to end and the strips are placed so that the opposite open ends of the grooves align with the aforesaid short grooves 5 in the measuring strips. In other words, a wooden strip 6 is placed opposite each pair of opposed grooves 5. The grooves 5 and 7 constitute guides or passageways for the cutting implement used in severing the fabric. For the purpose of providing a more rigid structure, small metal plates 8 are fastened to the opposite end of each of the strips 6, portions of the plates being allowed to project beyond the ends, and these projecting portions being formed with holes 9 for passage of the aforesaid fastening screws. With this arrangement it should be observed that the fastening screws serve first to retain the measuring strips in place and also pass through the holes in the metal anchoring plates 8 for retaining the strips 6 in place. It is yet to be pointed out that these

grooves in the measuring strips and wooden strips are disposed at predetermined longitudinally spaced points, each point indicating a specified portion of a yard. For instance, the grooves on the right hand end of the device are one-eighth of a yard apart, while the distance between the first groove on the right hand end and the third groove is a distance equal to one-quarter of a yard.

From the foregoing it is obvious that in using the device, the employee places one edge or end of the fabric directly above the outermost right hand groove and stretches the fabric over the frame to any desired point. For instance, if the customer wishes one-half of a yard of the fabric, the fabric is stretched over and beyond the center of the device wherein an indication appears giving that particular measurement. With the assistance of a customer, the material is held in proper position and the blades of the scissors are guided through the selected grooves while the fabric is being severed. A perfectly straight edge is thus always left on the end of the material still on the bolt and an accurate measurement is assured and with such a device, there is no chance for short-measure or wastage of material. Solicitation of samples by customers is also avoided to very noticeable extent by the presence of the true edge left on the end of the fabric after the desired amount has been removed.

It is within the scope of the invention, as before intimated, to either apply the device as an attachment to a counter, to build it in the top of the counter, or to movably mount it upon the counter so that it can be transported from place to place for more convenient use. It is thought however that the foregoing description taken in connection with the drawing will enable the reader to obtain a clear comprehension of the invention and for this reason a more elaborate description is deemed unnecessary.

Attention is directed to the fact that the combination of materials specified is intend-

ed very desirable. That is, the measuring strips are of metal to render them warp proof and to provide the desired straight edges for securing accurate measurements, and the cross strips are of wood. By using wood, objectionable clinking noise which would result from the contact of the scissor blades with metallic material, is entirely avoided.

Having thus described the invention, what I claim is:—

1. A fabric measuring device comprising a pair of warp-proof metallic straight edges disposed in transversely spaced parallelism and calibrated and provided at longitudinally spaced points with transverse grooves, the grooves in one straight edge being opposed to the grooves in the other straight edge, and strips interposed between said straight edges and having grooves in their upper sides aligned with and opening into the opposed grooves in said straight edges, said strips being made of wood to eliminate objectionable noises produced by metallic cutting implements.

2. A fabric measuring device comprising a pair of transversely spaced metallic straight edges having their upper sides calibrated and formed at longitudinally spaced points with grooves, the grooves in one of the straight edges being in alignment with the corresponding grooves in the complementary straight edge, and a plurality of longitudinally spaced separate and independent strips of wood interposed between the straight edges, said wooden strips being provided in their upper sides with grooves, said last named grooves aligning with the opposed pairs of grooves in the aforesaid straight edges, and connecting plates connected to the opposite ends of the wooden strips and projecting beyond said ends and underlying the straight edges, said connecting plates being apertured for passage of fastenings.

In testimony whereof I affix my signature.
JAMES HERBERT McDERMOTT.
